UNITED STATES PATENT OFFICE

157,101

VENDING MACHINE

Edward L. Strempel, Bedford Village, N. Y.

Application November 16, 1948, Serial No. 149,669

Term of patent 7 years

(Cl. D52—3)

To all whom it may concern:

Be it known that I, Edward L. Strempel, a citizen of the United States and resident of Bedford Village, in the county of Westchester and State of New York, have invented a new, original, and ornamental Design for a Vending Machine, of which the following is a specification, reference being had to the accompanying drawing, forming a part thereof.

The figure is a front perspective view of a vending machine, showing my new design.

The design is characterized by a generally rectangular vertical cabinet having a semi-tubular projection from the front face thereof in which is embodied a station for positioning a cup to receive the beverage vended, a curved transparent glass door being used to provide visibility, and the semi-circular projection on the front from a point below this station tapers downwardly in a conical manner and terminates at a point adjacent to the bottom thereof, and the cabinet has

a top which is beveled over to match the beveled top of the body of the cabinet and coincides with the semi-circular projection on the front thereof. The left side of the cabinet is substantially the same in appearance as the side shown, and the rear of the cabinet is plain.

I claim:

The ornamental design for a vending machine, substantially as shown and described.

EDWARD L. STREMPPEL.
